(57) **CLAIM**

The ornamental design for a display screen or portion thereof with graphical user interface, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first image in a sequence of a display screen or portion thereof with graphical user interface, showing the new design;

FIG. 2 is a second image thereof; and,

FIG. 3 is a third image thereof.

The peripheral broken lines illustrate a boundary of a display screen or portion thereof which forms no part of the claimed design. The appearance of the graphical user interface transitions between the images shown in FIGS. 1-3. The process or period in which one image transitions to another forms no part of the claimed design.

The dot-dash broken lines show the bounds of the claimed design and form no part thereof. Both grayscale and color portions enclosed by the dot-dash broken lines form no part of the claimed design.
